UNITED STATES PATENT OFFICE.

FREDERICK C. OVERBURY, OF HILSDALE, NEW JERSEY.

DESIGN FOR A ROOFING ELEMENT.

53,086.

Specification for Design.

Patented Mar. 11, 1919.

Application filed August 12, 1915. Serial No. 45,251. Term of patent 14 years.

To all whom it may concern:

Be it known that I, FREDERICK C. OVERBURY, a citizen of the United States, and residing at Hillsdale, in the county of Bergen, State of New Jersey, have invented a new, original, and ornamental Design for a Roofing Element, of which the following is a specification, reference being had to the accompanying drawing, forming part thereof.

On the drawing,—

Figure 1 represents a plan view of a roofing element showing my new design.

Fig. 2 represents a portion of a roof covering consisting of roofing elements embodying the design.

I claim:

The ornamental design for a roofing element, as shown.

FREDERICK C. OVERBURY.
